UNITED STATES PATENT OFFICE.

JOHN GELL AND ROBERT GELL, OF ROCHESTER, NEW YORK.

MACHINE FOR APPLYING LIQUID CEMENT.

1,119,271.

Specification of Letters Patent.

Patented Dec. 1, 1914.

Application filed May 2, 1912. Serial No. 694,624.

To all whom it may concern:

Be it known that we, JOHN GELL and ROBERT GELL, citizens of the United States, and residents of Rochester, in the county of 5 Monroe and State of New York, have invented a new and Improved Machine for Applying Liquid Cement, of which the following is a specification.

This invention relates to means for applying liquid cement to articles in general and, also, to means for regulating the coating of cement applied thereby to the articles to be cemented, comprising adjustable means for variably predetermining the depth to 15 which the articles to be coated may be inserted within a bath of the cement in liquid form.

In the accompanying drawings we have shown that embodiment of our invention 20 more especially adapted to applying glue to the dovetailed ends of the sides of wooden boxes without, however, limiting ourselves to such or any embodiment or application thereof. In applying the glue to the ends 25 of the sides of such boxes, it is important to apply the glue simultaneously to the ends of a considerable number of the sides, and to this end we provide a reservoir for the heated glue with a perforated shelf supported below the surface of the glue therein 30 a distance substantially equal to the length of the tenons formed on the ends of the sides to the box, or the depth which the articles are to be inserted in the liquid glue. 35 In the use of such a device, however, the liquid glue above the shelf separates and becomes coated with a thin layer of chilled glue which adheres in strings to the articles to which it is applied causing very unsatisfactory results in that considerable quantities of glue are wasted and the work is more or less smeared therewith. To overcome this difficulty we provide a reciprocating blade 40 located and operating beneath the shelf in such a way as to maintain a constant circulation of the glue through the openings or holes in the shelf. In the use of such an apparatus it is difficult to regulate the flow of glue to the glue applying reservoir in 45 such a way as to maintain a constant depth thereof above the perforated shelf, as it frequently happens that the workmen do not handle or treat the sides of the boxes or articles to be glued with uniform rapidity

or in uniform quantities so that even were 55 the rate of supply of glue to the glue applying reservoir maintained practically constant and at such a rate as to maintain a constant level for any particular rate or speed of applying the same to the ends of 60 the box sides or articles to be cemented, a constant level for the glue in the applying reservoir can not be maintained. To overcome this latter difficulty we regulate the rate of supply of glue to the applying reservoir 65 so that the same will be slightly in excess of the demand, and we provide a pumping mechanism adapted to return to the glue heating reservoir the surplus glue in the glue applying reservoir tending to 70 accumulate above an adjustably predetermined depth over the shelf.

The accompanying drawings showing such an embodiment of our invention are as follows, —

Figure 1 is a plan view of our glue applying machine, while Fig. 2 is an elevation of the same as seen from the lower side thereof relative to Fig. 1. Fig. 3 is a transverse sectional view taken along the line $x-y$ 80 of Fig. 1. Fig. 4 is a front elevation of the machine, as seen from the left relative to Figs. 1 and 2, with parts of the heating jacket and glue applying reservoir broken away. Fig. 5 is an enlarged detail view 85 of the pumping mechanism showing parts of the main body of the machine in section. Fig. 6 is a vertical central sectional view through the pump itself, and Fig. 7 is a detail thereof to be explained. 90

Similar parts are designated by similar letters of reference.

Referring to the drawings, the main body portion of the machine, comprising a heating jacket T conformed as shown in Figs. 95 2, 3 and 4, is supported upon suitable legs t secured to the under side thereof. This heating jacket is formed in two parts, T^1 and T^2 , the latter part shown to the right in Figs. 1, 2 and 3, having side walls extending all around the same and terminating at their upper edges in a continuous flange f^1 . The front wall t^1 extends only part way down to the bottom t^2 and has at its lower edge a forwardly extending flange f^2 which, 105 in the preferably integral casting comprising the entire heating jacket, is extended into and is continuous with the flanges f^1 on

the upper edges of the side walls t^1 of the front and shallow portion T^1 of the jacket T . The front and rear portions T^1 and T^2 of the jacket T have their two opposite side walls extending in the same plane.

A glue pot P is supported within the portion T^2 of the jacket T by a continuous flange f extending outwardly from the side walls thereof, near the top, resting upon and bolted to the flange f^1 extending around the top of the four walls of the portion T^2 of the heating jacket. A glue applying reservoir D is similarly supported, by means of flanges f^2 , within the forward portion T^1 of the jacket. The glue heating pot and the glue applying reservoir are spaced from and inside of the walls of the heating jacket in order that the steam or hot water may extend around and on all sides thereof and within the jacket T . The bottoms of the reservoir D and of the glue heating pot P are slightly inclined downwardly to the front thereof as indicated in Fig. 3 in order that the contents may be drained therefrom. Within the glue heating pot P there is provided a partition p extending from front to rear and located nearly in the center thereof dividing such glue pot into two portions, the larger one of which 1 is for receiving the glue to be heated and melted, and this partition p is provided with an opening o therethrough at its lower edge and near the front to provide a passage for the glue from the larger portion 1 into the discharging reservoir 2. This discharging reservoir 2 is separated by a transverse partition p^1 from a chamber 3 of nearly equal size and similar proportions, which is provided with a cover J having two circular openings therethrough each adapted to receive the usual portable glue pot J^1 . The glue as it is heated and melted in reservoir 1 passes through the opening o in the partition p into the discharge reservoir 2 and out through the discharge pipe v , threaded through the boss on the lower front wall thereof, and through the regulating valve V threaded onto such discharge pipe.

The glue applying reservoir D is provided with a drainage pipe v^1 , which is normally closed by a valve V^1 , for the purpose of draining the contents therefrom. The jacket T is also provided with a drainage pipe O^1 , secured in the boss on the bottom wall thereof at its front edge, and is provided with a valve V^2 for normally closing the same, and for this purpose the bottom of the jacket T may be slightly inclined preferably to the front to more completely drain the contents therefrom.

An intake pipe O connected with any suitable supply of steam or hot water is provided, while an overflow or discharge pipe O^1 is also provided in order to permit of a continuous intake of steam or hot water

into the jacket T . A perforated shelf I is suitably supported within the reservoir D and upon lugs d at the corners thereof.

Extending to the rear from the jacket T are seen two brackets Z in which are formed 70 bearings z for a shaft S carrying the usual loose and tight pulleys U and U^1 for operating the shaft; and on this shaft there is also secured a spur gear g meshing with a larger spur gear G secured upon a shaft S^1 75 journaled in bearings z^1 also carried by the brackets Z . On the outer end, being the lower end in Fig. 1 and the end toward the observer in Fig. 2, of the shaft S^1 is secured a crank disk W provided with a crank pin 80 upon which is secured a revolute sleeve w which is pivotally secured by means of the usual set screws to the bifurcated head r on the rear end, or right hand end with reference to Fig. 2, of the connecting rod R , having on its left hand end in turn the bifurcated head r^1 making pivotal connection with the short link r^2 bifurcated at its forward, or left hand end with reference to Fig. 2, and pivotally secured to one end of 90 the bell crank lever L , to the other end of which there is pivotally secured the bifurcated head r^3 on the right hand end, with reference to Fig. 4, of the connecting rod R^1 having on its left hand end the bifurcated 95 head r^4 pivotally connected in turn with the crank L^1 on the upper end of a shaft M , rotatable in bearings b^1-b^2 formed on the front wall t^1 of the rear portion of the jacket T and held against longitudinal and vertical 100 movement within such bearings by means of collars secured on such shaft, as indicated. The lower end of this shaft M extends, through an opening therefor in the perforated shelf I and has secured thereon below each shelf, a blade M^1 adapted on the oscillation of the shaft M to move to and fro within the reservoir D beneath the shelf I for the purpose hereinafter explained.

The bolt or stud made use of for pivotally 110 connecting the bifurcated head r^3 with the bell crank lever L extends upwardly through a sleeve r^5 rotatably secured thereon and pivotally connected with this sleeve is seen the bifurcated head r^6 on the right hand 115 end, with reference to Fig. 4, of the connecting rod R^2 , having on its left hand end the bifurcated head r^7 pivotally connected with the upper end of the bell crank lever L^2 120 oscillably supported upon a stud s^1 and held in place thereon by any suitable mechanism such as a cotter key. This stud s^1 is secured in a bracket b^3 extending downwardly from and secured on the under side of the flange f^1 at the front side of the rear section of the heating jacket T . The other arm of this bell crank lever L^2 is pivotally connected with the bifurcated head r^7 adjustably secured on the upper end of the connecting rod R^2 , on the lower end of which 130

is adjustably secured a bifurcated head r^8 pivotally connected, as seen, with the extension e formed on the upper end of the pump plunger E reciprocating vertically within the bore a of the pump body A .

The pump body A is formed preferably from an integral casting provided with lugs or ears h by means of which the same is secured by bolts, extending through suitable 10 spacing blocks as indicated, to the rear wall of the reservoir D . This casting A is bored out to form a chamber a having a duct a^1 at its lower end extending into the bored channel a^2 which may be closed by means of a 15 screw plug a^6 and which, also, connects with the vertical channel a^8 having at its upper end a valve seat provided for the ball valve a^5 , above which is seen the chamber a^4 threaded at its upper end to receive the connecting member k to which in turn there is 20 threaded the pipe K leading upwardly and discharging into the heating reservoir 1 .

Through the body A of the pump there is formed an opening c^1 the relative size and 25 location of which is indicated in Figs. 5 and 7. In front of this opening c^1 and for the purpose of effecting a predeterminedly variable closure thereof, there is provided a plate C vertically slidable upon the screws n , engaging through slots therefor in the plate C and threaded into the body A as indicated 30 in Fig. 5, and held in any desired position of vertical adjustment by means of the thumb nut N threaded onto a stud secured in the casting A and extending through a slot therefor in the plate C . The upper end of 35 the plate C may have an extension adapted to be engaged by the hand of the operator; while at the left hand edge of the plate there may be formed an indicator coöperating 40 with a scale, marked off on the face of the body A , to gage and indicate the different depths to which the glue is permitted to rise above the perforated shelf I by the correspondingly different adjustments of the 45 plate C . An opening, as indicated at o^1 , is provided through the front wall of the pump body A extending into the chamber a^4 at its lower end at a point just where the 50 contents will be drained therefrom when the swinging button release valve m is moved to the open position indicated in Fig. 5, the valve m being normally positioned to close the opening o^1 . This valve m is provided in 55 order to drain off the glue at any time when the machine is to become idle so that the valve may not be set in the glue or the glue permitted to harden around the valve a^5 at the lower end of the chamber a^4 .

60 In the use of such a machine, it frequently happens that chips and like articles from the articles being glued gather and accumulate on the surface of the glue in the reservoir D which would interfere with the proper action of the pump and the valve a^1 . To pre-

vent such chips from entering through the opening c^1 there is provided a shield A^1 , seen in Figs. 3, 5 and 7, formed of thin sheet metal screwed to the body of the pump A and extending outwardly and forwardly 70 from the body of the pump A so as to permit the glue to enter thereunder and between the same and the front face of the pump and into and through the opening c^1 in the pump body.

In using our glue applying machine, the reservoir 1 in the glue heating pot P is filled with the glue to be heated and melted which, as it is heated and melted, passes through the opening o into the discharge reservoir 2 80 and therefrom outwardly through the discharge pipe v , the rate of flow therethrough being regulated by the valve V . The glue in the heating pot P and in the applying reservoir D is maintained at the desired temperature by the means and in the manner already indicated. The glue as it escapes into the reservoir D is allowed to rise in the reservoir D to the height determined by the adjustment of the plate C . Power is applied 85 in the usual way, preferably by means of a belt engaging over the pulley U^1 , causing the shaft S to rotate, from which, in turn, the shaft S^1 is rotated through the connections already described; the rotation of 90 which upper shaft S^1 causes, through the mechanism already described, the to and fro movement of the blade M^1 and also causes the operation of the pump already described. The plate C is adjusted so that the bottom 95 of the opening therethrough c is at the level of the top of the glue which it is desired to maintain above the shelf I , and the vertical adjustment of this plate C is sufficient to provide in this way for any desired depth 100 of the glue above the shelf I . The opening c^1 through the body of the pump into the bore thereof a , should of course extend above the bottom of the opening c through the plate C , for the highest adjustment thereof, 105 in order that there may be provided an escape for the surplus glue through such opening c^1 in the body of the pump. After such adjustment the machine is in readiness for use and the sides of the boxes are glued in 110 bunches of suitable number by standing them on their tenon or dove tailed ends on the shelf I . The operation of the blade M^1 in the reservoir D and beneath the shelf I causes a continual circulation, through the 115 openings in this shelf I , in such a way as to prevent the separation of the glue above the shelf and the formation on the surface thereof of a skin of chilled glue which would otherwise be formed and would adhere in 120 strings to the sides of the box as they are removed and cause a smearing of the sides of the box or of the articles to be glued as they are being handled and also would result in a needless waste of considerable glue. 125 130

It is believed from the foregoing description of the glue applying machine in accordance with our invention that the operation thereof and method of using the same is 5 sufficiently clear to call for no further consideration herein.

A pipe v^8 , connected with the heating jacket T and provided with a valve V^8 , discharges hot water therefrom into the upper 10 end of a pump cylinder a to prevent the accumulation of hardened glue at the upper end thereof. The glue, as it is carried upwardly in the pump cylinder by the piston E, would tend to accumulate in a hardened 15 mass around the upper end of the pump cylinder and just sufficient water is thus discharged into the upper end of the pump cylinder, usually in a very fine stream or in a succession of drops, to soften the glue 20 which would otherwise accumulate in a hardened mass and interfere with the free operation of the pump. The amount of glue which is thus carried up to the upper end of the pump cylinder, while practically insignificant 25 as to the loss incurred thereby, frequently becomes sufficient to materially interfere with the successful operation of the pump. The glue as it thus accumulates and is softened or reduced to the liquid state 30 is carried upwardly and discharged over the upper edge of the pump cylinder and into the reservoir D.

What we claim is:

1. In a cement applying machine, a heating jacket having suitable inlet and outlet connections, a glue pot supported in said jacket and comprising a receiving and a discharging reservoir, a glue applying reservoir supported in said jacket below and to 35 one side of said glue pot, a pipe leading from said discharging reservoir to said applying reservoir and containing a regulable valve, a perforated shelf in said applying reservoir for supporting the articles to be cemented, a shaft extending through said shelf and means for revolubly and adjustably supporting the same, an agitator for 40 maintaining a circulation of the cement in the applying reservoir through the openings in said shelf, such agitator comprising an arm carried by said shaft and located in the applying reservoir below the perforated shelf, a bell crank lever oscillably supported 45 on said jacket, means for actuating said lever, and connections between said lever and said shaft for causing an oscillatory movement of the shaft.

2. In a cement applying machine, a heating jacket having suitable inlet and outlet connections, a glue pot supported in said jacket and comprising a receiving and a discharging reservoir, a glue applying reservoir supported in said jacket below and to 50 one side of said glue pot, a pipe leading from said discharging reservoir to said applying reservoir and containing a regulable valve, a perforated shelf in said applying reservoir for supporting the articles to be cemented, a shaft extending through said shelf and means for revolubly and adjustably supporting the same, an agitator for 55 maintaining a circulation of the cement in the applying reservoir through the openings in said shelf,

reservoir for supporting the articles to be cemented, a shaft extending through said shelf and means for revolubly and adjustably supporting the same, an agitator for maintaining a circulation of the cement in 70 the applying reservoir through the openings in said shelf, such agitator comprising an arm carried by said shaft and located in the applying reservoir below the perforated shelf, operating means connected to said shaft for causing the actuation of said agitator, means for automatically maintaining a variably and adjustably predeterminable depth of the liquid cement above said shelf comprising a pump located in the applying reservoir and arranged to receive the liquid cement therefrom and force the same into said receiving reservoir, means for actuating said pump, and means for variably predetermining the level above said shelf at which 75 the liquid cement enters the pump.

3. In a cement applying machine, a heating jacket having suitable inlet and outlet connections, a heating reservoir supported in said jacket, a glue applying reservoir supported in said jacket below and to one side of said heating reservoir, a pipe leading from said heating reservoir to said applying reservoir and containing a regulable valve, a perforated shelf in said applying reservoir for supporting the articles to be cemented, a shaft extending through said shelf and means for revolubly and adjustably supporting the same, an agitator for 90 maintaining a circulation of the cement in the applying reservoir through the openings in said shelf, such agitator comprising an arm carried by said shaft and located in the applying reservoir below the perforated shelf, a bell crank lever oscillably supported 95 on said jacket, means for actuating said lever, and connections between said lever and said shaft for causing an oscillatory movement of the shaft.

4. In a cement applying machine, a heating jacket having suitable inlet and outlet connections, a heating reservoir supported in said jacket, a glue applying reservoir supported in said jacket below and to one side of said heating reservoir, a pipe leading from said heating reservoir to said applying reservoir and containing a regulable valve, a perforated shelf in said applying reservoir for supporting the articles to be cemented, a shaft extending through said shelf and 100 means for revolubly and adjustably supporting the same, an agitator for maintaining a circulation of the cement in the applying reservoir through the openings in said shelf, means for automatically maintaining a variably and adjustably predeterminable depth of the liquid cement above said shelf comprising a pump located in the applying reservoir and arranged to receive the liquid cement therefrom and force the same into said 105

110
